R. P. PESCARA

SYSTEM OF HELICOPTER SCREWS

Filed July 15, 1920

Inventor:
Raul Pateras Pescara,
By - B. Singer Atty

UNITED STATES PATENT OFFICE.

RAUL PATERAS PESCARA, OF BARCELONA, SPAIN.

SYSTEM OF HELICOPTER SCREWS.

Application filed July 15, 1920. Serial No. 396,597.

To all whom it may concern:

Be it known that RAUL PATERAS PESCARA, citizen of the Argentine Republic, and residing at Barcelona, Calle de la Buena 55
5 Suerte 20, Spain, has invented new and useful Improvement in Systems of Helicopter Screws (for which I have filed an application in Spain under date of July 3, 1919), of which the following is a specification.

10 This invention relates to a helicopter.

In matters dealing with helicopteration I designate by the word "screw" every organ adapted to give a pressure or drive by means of the rotation on an axis of surfaces constructed with or without helicoidal torsion.

The most simple solution of the general problem of direction, propulsion and stability of flying machines of the helicopter type, may be considered as by means of the 20 use of a system of two screws turning in inverse directions, which may be inclined from the vertical in any direction.

The problem having thus been stated theoretically it is not, however, an easy matter to give it a practical solution in consequence of all the complications which the realization of the inclining of the apparatus entails and which have to be overcome.

On the other hand, when it is considered, 30 that in case of the accidental stopping of one or more motors of the helicopter, the descent, under the action of the machine's own weight, would become accelerated in a manner to prove very dangerous, which would 35 result in finding oneself in the presence of serious difficulties not of the nature to encourage the studying and investigation of apparatus of this type.

As a matter of fact the use of two propellers turning inversely has for its object 40 to counteract or oppose the pivoting movement of the machine, such as the same would otherwise take up under the re-active influence of one single propeller.

45 It is therefore apparent that such an arrangement would not suffice in itself to assure the stability of the orientation of position. It is evident, also, that two propellers cannot be constructed with a rigorously exact perfection and that consequently 50 some slight differences in their angles of attack might exist in same. These discrepancies between the two propellers revolving in

inverse directions would necessarily entail a more or less rapid pivoting of the entire 55 machine itself.

On the other hand in order to effect the steering, the apparatus must change its orientation or position and it will be necessary to overcome this pivoting movement by 60 means of a special controlling or steering gear.

The system between the screws of sustentation, propulsion, stabilization, parachuting and differential warping in connection with 65 flying machines of the helicopical type as regards direction, propulsion and stability by inclining which is the objective of the present descriptive account, is destined to give a practical solution, by its sole action, 70 of the problem of:—

Direction;

Propulsion; and

Stability;

Easy descent without dependence on motive power; 75

Braking the descent when landing;

Stability of position (orientation) by the use, for obtaining these respective effects, of:— 80

Periodical differential warping.

Periodical and variable differential incidence.

Simultaneous diminution and increase of 85 the angle of attack of the propeller blades.

Differential warping between the propellers of the system.

In a general way, it is to be understood that, by the warping of the propeller blades, is meant a mechanical action which 90 consists of causing a varying in the angle of attack of the surfaces formed by the said blades, in such manner that this variation only affects one part—more or less extended—of the total surface of the blades. 95

The warping will be termed differential if, to an increase of incidence in one blade, there corresponds, at the same moment, a co-relative diminution in the opposite blade. In short, I will designate it as periodical differential when the differential variation of the angle of attack is reproduced periodically at each revolution of the blade. 100

The same definitions should be understood of the periodical, variable differential variation of incidence, with the sole difference 105

that the variations of the angle of attack (as mentioned in the foregoing) affect the total of the surfaces which constitute the blades.

5 I term simultaneous decrease or increase of incidence in propellers, those screws constructed in such manner, that it is possible, during flight, to diminish or increase the incidence of their blades; the diminution 10 brought about at any given moment being equal as regards all the blades of the propeller under consideration.

In fact, the warping, which we have already defined above, will be designated differential as between the screws of the system, if, at the same time that the angles of attack in all the blades of one propeller are increased (that is to say partially) by means of the action of warping, a diminution is made in the same manner of these 20 same corresponding angles on the other propeller of the system.

At the outset I will demonstrate the analogy which exists between the variable 25 periodic warping, and the variable periodical variation of incidence.

From these definitions it is evident that the warping, which affects a portion (generally a small part only) of the surfaces which 30 form the blades, allows of efforts much more graduated in intensity being obtained than with the variation of differential incidence. I therefore consider it as an improvement of the variable incidence, and to summarize 35 it, I will consider and deal with the possibility of using them in one of the three following manners:

(1). Variable incidence alone;
(2). Warping alone;
40 (3). Warping and variable differential incidence, in combination.

But, inasmuch as the reasoning which can be applied to the above is the same both for the warping and the variation of incidence, I will only speak of the warping 45 with a view to simplifying matters. It will be understood, therefore, that in the following remarks all that I state as regards the one applies equally to the other.

50 It is known that the periodical differential warping allows of the centering of the drive or push given by the propellers and consequently to bring into effect a couple of forces capable of inclining the apparatus. The result of this inclining is the formation of a 55 horizontal component of the drive which brings about a translation in a determined sense. The problem therefore, as regards propulsion and direction, is solved in this 60 way.

The stability problem cannot be solved otherwise than by an intervention of an antagonistic couple of forces which jointly oppose the perturbating couples due to 65 atmospheric action of every kind. The pe-

riodical differential warping consequently resolves also this problem, because it brings about the necessary couple of adjusting and righting forces.

I will now demonstrate how the simultaneous diminution allows of obtaining an easy descent without making use of motive power, that is to say, what I call a rotating direct "vol plane." Under this designation is to be understood the descending movement (of an "helicoptic" machine) retarded by the push due to the screw blades of same. 70 75

In order that this auto-rotation should be efficacious it is necessary that it should be in accordance with a systematized rule corresponding to the angle of attack in which the relation between the resistance and the push shall be at its minimum (or in the proximity of minimum) as near as it is possible to be obtained with the profile of the 80 blades adopted, and in order that this condition can be established, the normal rotating speed of the blades must be maintained, however, diminishing instantaneously their 85 angle of attack before the velocity of the 90 fall becomes too greatly accelerated.

This diminution of incidence in all the blades corresponds to the definition I have given, i. e., simultaneous diminution of incidence. This therefore allows of accomplishing the direct rotating "vol plane." 95

A sharp increase inversely will permit of braking the descending movement at the moment of landing. In fact, from the general definition of differential warping between the two screws, it is easily deducted that, if a difference exists between the angles of attack of the said screws the same can be easily corrected by increasing the incidence of the screw that offers the least turning resistance, and reducing it in the one that presents the great resistance. In an analogous manner, it is evident that this same maneuver can give rise to an inequality which will allow of altering the orientation and direction of the courses steered. 100 105 110

This being demonstrated, I shall now proceed to indicate the practical realization of such propelling screws. The drawing attached hereto, represents a comprehensive vertical section of the central portion of the screws. 115

In the drawing: The central tube, serves as an axis in common for the two screws 2 and 3 and the bosses or hubs 4 and 5 of which are connected up by means of ball bearings 6, 7, 8 and 9. The central tube is constructed of two pieces joined together by the intermediate section 10 which serves at the same time as a support for the conical pinions 11. These pinions reverse the movement of the screw propeller 3 while it transmits movement to the screw 2 through the intermediary of the tooth crowned wheels 12 and 13. 120 125 130

To make the matter clearer I will divide my description in such manner as to indicate separately the various organs, or component parts they operate.

- 5 (1). The differential periodic warping;
- (2). The simultaneous diminution or increase of incidence in propeller blades.
- (3). The differential warping as between the two screws.

10 *Periodic differential warping.*

The rod 14 is mounted for universal movement as at 15; at 16 and 17 two socket joints are fixed and carry the arms 18 and 19 which traverse the central tube crossing the grooved sockets and which are fixed into the ball bearings at 20 and 21.

15 The outside ring of these bearings carries, facing each blade, small connection rods 22 and 23 which are articulated therein. At its other end this rod is joined by another articulation to spindles or guide rods 24 and 25 which are slidable in the inside of the tubular longitudinal frame bearers 26 and 27. Cables 28 and 29 which operate the warping appliances are attached to these guide rods. It might be well to here recall that by warping appliance is meant any apparatus which, by its direct action on the 20 air, tends to increase or reduce the angle of attack, or the push or drive of the blade in the region equipped with such an arrangement.

25 This warping or winding appliance may be constructed in several equivalent ways: for instance, by a special construction of the blade which allows the variation of its curved surface in a certain region, or else by a wing that is capable of being trimmed while also being movable around a horizontal axis. I will assume that this second type has been adopted and this appliance is operated by the intermediary of an endless screw which transforms the tension or relaxation of the cable in rotating movements 30 of the sail or wing.

35 It is to be noted that these endless screws must have contrary inclinations in respect to the screws 2 and 3 so that by a tension applied to the cable 28 or a relaxation of cable 29 an identical movement is applied to the respective wings or sails of the two screws.

40 It is easy to understand that, if the pilot inclines the rod 14 the angles of attack of the left of the blades will be diminished. The small connecting spindles 22 and 23 have their articulation in the ball bearings 20 which allows of the eccentric action of the bearing 20 without interfering with the 45 rotating movements of the screw propellers.

45 *Diminution or increase simultaneously in the incidence of the propeller blades.*

50 The lever 30, under the manual control of

the pilot, operates through the medium of a crank 31, several guides such as 32, 33 and 34 linked up to each other by spindles 35 and 36; under the impulse exerted of the lever 30, the entire system of guides and spindles can be made to rise or to descend by the sliding displacement in the inside of the tube 1. The guides 33 and 34 serve to support the interior ring of the ball bearings 37 and 38 by the intermediate use of 55 arms traversing the central tube 1.

To the outer ring of these bearings are attached, facing each blade, the small connecting links 39 and 40 of which the other ends are attached to the parts 41 and 42 which constitute screws, the threads of which are very long. The sleeves 41 and 42 are provided on the outside with rectilinear grooves 43 and 44 which adjust themselves in corresponding grooves provided by supporting arms 45 and 46.

60 In the interior of the screws 41 and 42 are the frame supports 26 and 27, these being tapped to the same screw thread.

65 It is therefore obvious, that if the pilot 60 operates the lever 30 in such manner, for example, as to cause the guides 33 and 34 to ascend, and with them the ball bearings 37 and 38, then the small connecting spindles 39 and 40 will force the threaded 65 sleeves 41 and 42 to approach to or recede from the axis of the apparatus. Inasmuch as these sleeves cannot turn on themselves on account of the grooves 43 and 44 it is the threads of these which forms a solid 70 part of the frame bearers 26 and 27, which turn on themselves, by communicating their movement to the blade in its entirety thus bringing about a diminution or increase of 75 incidence throughout every part of the 80 screw or propeller.

85 *Differential warping between the screws.*

90 I have already indicated how the controlling operation of the periodic warping 90 is effected by means of the rod 14. At 47 is a wheel which allows the rod 14 to be turned on itself. This movement of the before mentioned rod is transformed, by means of the screw 48, into one of ascent or descent of the same in its entirety. The 95 socket joints 16 and 17 are then obliged to follow up in this movement simultaneously with the ball bearings 20 and 21. The small spindles 22 and 23 convert this vertical movement into a horizontal displacement of the guide rods 24 and 25. If, for 100 instance, the rod 14 has ascended those at 24 and 25 will come nearer the axis of the apparatus while bringing about a tension on 105 all the cables.

110 I have already explained that this tension is transformed in the screw 2 into a partial increase in the incidence of the 115 blades; and in the screw 3 to a diminution 120

of such incidence. In this way the differential warping between the two screws is obtained.

From the general arrangement which the drawing shows it can be deduced that the operating control of these various actions, i. e. periodic differential warping; simultaneous diminution or increase of incidence; and differential warping between the screws, 10 are completely independent of each other.

While, in the foregoing, I have described the specific embodiment of the invention, as shown in the accompanying drawing, it is nevertheless to be understood that in carrying the invention into practice I may resort to any and all modifications falling within the scope of the appended claims.

I claim:

1. In a helicopter, a pair of oppositely rotating propellers each having movable blade portions, a central hollow spindle mounting said propellers for rotation thereon, and mechanism including elements within said spindle for adjusting the blades and 25 movable portions thereof independently.

2. In a helicopter, a pair of propellers having blades, a central spindle mounting said propellers for rotation thereon in opposite directions, said blades having movable portions, ring members floating on said spindle and connected with the movable portions of said blades, and a control rod passing through said ring members and fulcrumed therebetween whereby angular movement of said rod displaces the ring members to actuate the movable blade portions. 30

3. In a helicopter, a pair of propellers having movable blades, a central spindle mounting said propellers for rotation thereon in opposite direction, said blades having movable portions, ring members floating on said spindle and connected with the

movable portions of said blades, a control rod passing through said ring members and 45 fulcrumed therebetween whereby angular movement of said rod displaces the ring members to actuate the movable blade portions, and means for actuating the movable blades. 50

4. In a helicopter, a pair of propellers having movable blades, a central spindle mounting said propellers for rotation thereon in opposite directions, said blades having movable portions, ring members floating on said spindle and connected with the movable portions of said blades, a control rod passing through said ring members and fulcrumed therebetween whereby angular movement of said rod displaces the ring 60 members to actuate the movable blade portions, and means slidably within the spindle for actuating the movable blades. 65

5. In a helicopter, a pair of propellers having movable blades, a central spindle 70 mounting said propellers for rotation thereon in opposite directions, said blades having movable portions, ring members floating on said spindle and connected with the movable portions of said blades, a control rod passing through said ring members and fulcrumed therebetween whereby angular movement of said rod displaces the ring members to actuate the movable blade portions, means for actuating the movable 75 blades, and means for moving the control rod along its axis.

In testimony whereof I, RAUL PATERAS PESCARA, have signed my name to this specification in the presence of two subscribing 80 witnesses.

RAUL PATERAS PESCARA.
